(57) **CLAIM**

I claim the ornamental design for the wetsuit entry device, as shown and described.

DESCRIPTION

FIG. 1 is a top view of the wetsuit entry device.

FIG. 2 is a bottom view of the wetsuit entry device.

FIG. 3 is a left side view of the wetsuit entry device, the right side view being a mirror image.

FIG. 4 is a front view of the wetsuit entry device.

FIG. 5 is a back view of the wetsuit entry device; and,

FIG. 6 is a perspective view of the wetsuit entry device.
